DESIGN FOR A WOVEN TEXTILE FABRIC

John L. Walther, New York, N. Y.

Application July 1, 1936, Serial No. 63,596

Term of patent 3½ years

To all whom it may concern:

Be it known that I, John L. Walther, a citizen of the United States of America, residing in city of New York, county of New York, and State of New York, have invented a new, original, and ornamental Design for a Woven Textile Fabric, of which the following is a specification, reference being had to the accompanying drawing, forming part thereof.

The figure of the drawing is a plan view of a woven textile fabric showing my new design.

The design comprises a series of diagonal lines running parallel to each other, and a series of slubs and French knots embroidered on the diagonal lines. The surface of the fabric is penetrated by fine hairs.

I claim:

The ornamental design for a woven textile fabric substantially as shown and described.

JOHN L. WALther.
